SORTING APPARATUS

Merle W. Kremer, Cleveland Heights, and Woodrow W. Heigle, Cleveland, Ohio, assignors to General Electric Company, a corporation of New York

Application April 24, 1948, Serial No. 23,118

4 Claims. (Cl. 209—99)

1

Our invention relates to inspection apparatus for automatically sorting cylindrical articles having component parts or sections of different diameters. More particularly our invention relates to apparatus for sorting composite wires having component sections of different diameter, which apparatus automatically separates acceptable wires from defective wires lacking one or more sections.

In the usual manufacture of composite wires such as those used as leading-in wires for radio tubes, incandescent lamps and the like, and consisting of sections of wire of different diameter welded in end-to-end relation, some of the wires are defective in that they have loose or unwelded sections. The apparatus of our invention is particularly useful for separating out the incomplete wires and can be used to advantage directly with the weld-making apparatus or in conjunction with other manufacturing apparatus which incorporates said wires into component parts of the lamps or tubes.

One object of our invention is to materially reduce the expense and eliminate human error in the inspection of bulk groupings of short wires comprised of two or more sections welded in end-to-end relation and of different diameter. The inspection operation involves the separation of wires having a particular number of sections and, therefore, a certain balance, from defective shorter wires of a lesser number of parts, regardless of which parts the shorter wires are comprised. These shorter, incomplete wires have heretofore been separated from the acceptable composite wires by manual inspection methods which have been unsatisfactory because of the cost and the detailed and tedious nature thereof.

Another object of our invention is to provide apparatus for automatically separating from a grouping of acceptable wires having portions varying in diameter those unacceptable wires that have either a diameter less than that of the largest portion of the acceptable wire or a considerably different weight distribution. The function of the apparatus requires that the acceptable composite wire be so proportioned that the weight of one or more of the smaller diameter (but longer or heavier metal) portions is capable of tipping the wire to an upright position when said wire is placed between two members spaced just slightly less than the diameter of the largest portion and more than the other portions. The two members provide a support upon which the largest diameter portion of the composite wire can rock as the weight of the

2

smaller diameter portion swings it down therebetween. Apparatus for separating out unacceptable wires in the above manner is particularly adapted to inspect groupings of two and three part composite leading-in wires used in the manufacture of radio tubes and lamps.

Other objects and advantages of our invention will appear in the detailed description which follows of the species thereof shown in the drawing.

In the drawing, Fig. 1 is a perspective view of apparatus comprising our invention; Fig. 2 is a side elevation of said apparatus; and Fig. 3 is section through a few of the separation rods along line 3—3 of Fig. 2 on a larger scale; and Fig. 4 is an elevation of a portion of several of the said separation rods.

The species of our apparatus appearing in the drawing receives a steady supply of wires to be inspected from the chute 1 which is located over the right-hand end thereof (Figs. 1 and 2) and by its operation causes acceptable three-part butt-welded wires 2 to drop in corresponding end-for-end relation into the shipping carton 3 below the left-hand end thereof. All two-part, single-part and improperly proportioned wires collect behind the door 4 at the bottom of the chute 5 midway along the near side of the apparatus.

The wires to be inspected fall from the chute 1 to the inclined bed 6 which is located above the right-hand end of the hopper 7, and are gradually shaken to positions between the rods 8 comprising said bed 6 and, if possible, down the inclined paths formed between the rods 8 by the constant vibrating motion to which the entire apparatus is subjected. The rods 8 are mounted at opposite ends on the cross members 9 and 10 which bridge the hopper 7 and are disposed as shown in Fig. 3 at a fixed spacing that allows all parts of the wires being inspected, except the largest 11, to fall through slots 8' defined by adjacent rods. This manner of mounting the rods 8 causes the vibrations of the hopper 7, which is

attached directly to the saddle 12 of a commercial electric vibrator 13, to agitate the wires to such an extent that they gradually separate from each other and shift about within the confines of the bed 6 and the enclosure 14 extending along the end and both sides thereof, to a properly orientated position between adjacent pairs of rods 8. The vibrations have a period corresponding to the 60 cycle current supplied to the inductance coil 15 which is mounted on the base 16 of the vibrator 13 and have a direction per-

pendicular to the leaf springs 17-17 by which the saddle 12 of said vibrator 13 is supported on the base 16 thereof. The amplitude of the vibrations, which are just discernible to the eye, is sufficient to cause the wires to shift about and to slide down the oppositely sloping surfaces presented by the rods 8 to the space therebetween. Means are provided by the pins or protuberances 18 located at random intervals along the upper sides of the rods 8 to assure the alignment of all wires therewith before they have traveled down the bed 6 to a position beyond the extent of the enclosure 14.

As shown in Fig. 3, an acceptable three-part wire 2 takes an upright position between a pair of adjacent rods 8 since the portion of largest diameter cannot fall therebetween and the weight of the smaller diameter, but longer, portions 19 and 20, which pass freely therebetween, is sufficient to swing the entire wire 2 to vertical position. Any wire consisting only of one or both of the smaller diameter portions 19 and 20 passes between the pairs of rods 8 and is caught on the bottom of the hopper 7 which also has a slight inclination causing the wires to move to the left and thence through the opening 21 and into the chute 5. The angular position of the partition 22 causes it to gather in the wires moving along the bottom of the hopper 7 and direct them toward the opening 21 in the wall of said hopper 7.

When a wire comprised only of the portion 11 of largest diameter, or of said portion 11 and the next adjacent portion 19, falls into the space between adjacent rods 8 it will assume a substantially horizontal position in alignment with the rods and will continue to be supported thereby. Posts 23 depending from each of the rods 8 at two points along their length are joined by cross bars 24 spaced below the rods 8 so as to be cleared by acceptable wires 2 and serve to assure the desired spacing and functioning of said rods 8. Accordingly, both the acceptable three-part wires 2 and the unacceptable wires, including the unwelded portions 11 of largest diameter, continue to move down the paths formed by the rods 8 and finally beyond the partition 22 to the adjacent portion of the hopper 7.

In the succeeding course of the movement, all the wires including the largest diameter portion 11 almost immediately come into position opposite notched portions 25 of the rods 8 which in effect widen the spacing therebetween for very short intervals of their length. As shown in Fig. 3, which is a section through the rods 8 at these notched portions 25, the spacing between the rods 8 at these notched portions is so great that the acceptable three-part wires 2, which are in an upright position, pass therebetween and drop onto the portion of the hopper 7 below. Other wires consisting only of the largest portion 11, or of portions 11 and 19, lie parallel to the rods 8 and, having a length more than twice the width of the notched portions 25, move over said notched portions with little or no interruption in their motion. The rear edges or shoulders 26 of the notched portions of the rods 8 are sloped or beveled to permit any wires entering the notches, but not falling into the hopper 7, to work themselves back onto a still lower portion of the rods 8.

In certain instances two or more acceptable three-part wires or another unacceptable wire arrive together at the first notched portion along the rods 8 so that interference develops to the

proper passage of the acceptable wire between the notched portions. In such instances the wires move further along the rods 8 and finally, if they are of an acceptable construction, pass through one of the succeeding notched portions thereof. A laterally extending and sloping trough 27 mounted adjacent the lower ends catches the incomplete wires consisting of the largest diameter portions 11, which travel the full length of the rods 8, and conducts them to the opening 28 in the hopper 7 where they fall into the chute 5.

The acceptable three-part wires 2 falling onto the hopper 7 are caused to move toward the left end thereof by the continuing vibration and slope of the hopper bottom. The course of movement of these wires 2 under the trough 27, which is located above the bottom of the hopper 7, and thence against the upright Y-shaped guideway 29 thereon which directs them into the three holes 30. The diameter of the holes 30 is just large enough to allow the wire 2 to tip and fall therein when the end comprised of the heavy larger diameter portion 11 passes over one of the holes. An oppositely orientated wire 2 having the smaller diameter portions 19 and 20 over the holes 30 does not fall thereinto as an unsupported length thereof equal to the diameter of the holes 30 is not sufficient to tip said wire 2. Accordingly all of the wires 2 fall in a correspondingly orientated manner through the funnel 31 and into the packing carton 3.

All of the incomplete wires collect at the bottom of the chute 5 which can be emptied as required by means of the door 4. Manual pressure against the top of the door 4 swings it about the hinge pin 32 against the action of the torsion spring 33 and allows the wires trapped therein to slide out the sloping bottom of the chute 5.

What we claim as new and desire to secure by Letters Patent of the United States is:

1. Apparatus for sorting completed cylindrical articles such as composite lead-in wires having end sections of different diameter and weight, the smaller-diameter sections being heavier than the larger-diameter sections, from incomplete articles constituted of one or the other such sections, said apparatus comprising an inclined bed portion comprising a plurality of parallel elongated cylindrical rods arranged in side-by-side relation, adjacent rods being spaced apart a distance intermediate the diameters of the larger and smaller sections of said articles to form slots therebetween whereby completed articles will upon end themselves in said slots and move downward therealong while loose smaller-diameter sections will fall through said slots and loose larger-diameter sections will lie flat between said rods and move downward therealong, portions of said rods at a plurality of points adjacent to but spaced from their lower ends being circumferentially notched to provide enlargements in the slots therebetween, each of said enlargements having a width greater than the diameter of said larger section of said article and a length less than half that of said larger section of said article whereby the upright completed articles will drop downward through the enlargements while the loose larger-diameter sections will pass over the enlargements to the lower ends of the rods, and means for supporting and vibrating said bed portion.

2. Apparatus as set forth in claim 1 wherein the upper sides of said rods are provided with a plurality of upstanding peg-like protuberances

which are engaged by articles moving along the upper surfaces of said rods in transverse relationship thereto whereby to orient said articles into the spaces between said rods.

3. Apparatus as set forth in claim 1 wherein those shoulders of said notches which are located toward the lower ends of the rods are beveled to permit articles entering a notch but failing to drop therethrough to work themselves back up into the slot beyond said notch.

4. Apparatus for sorting completed cylindrical articles such as composite lead-in wires having end sections of different diameter and weight, the smaller-diameter sections being heavier than the larger-diameter sections, from incompletely articles constituted of one or the other such sections, said apparatus comprising an inclined bed portion comprising a plurality of parallel elongated cylindrical rods arranged in side-by-side relation, adjacent rods being spaced apart a distance intermediate the diameters of the larger and smaller sections of said articles to form slots therebetween whereby completed articles will upward themselves in said slots and move downward therealong while loose smaller-diameter sections will fall through said slots and loose larger-diameter sections will lie flat between said rods and move downward therealong, portions of said rods at a plurality of points adjacent to but spaced from their lower ends being notched to provide enlargements in the slots therebetween, each of said enlargements having a width greater than the diameter of said larger section of said article and a length less than half that of said

larger section of said article whereby the upper completed articles will drop downward through the enlargements while the loose larger-diameter sections will pass over the enlargements to the lower ends of the rods, a hopper, means supporting said bed portion in said hopper above the bottom thereof, a partition extending along the bottom of said hopper transversely of the said bed portion and adjacent the notched portions of said rods to segregate the loose small-diameter wire sections from the acceptable articles, a trough extending transversely across the lower end of said bed portion above the bottom of the hopper to collect the loose larger-diameter wire sections falling from the end of said bed portion, and means for supporting and vibrating said hopper and bed portion.
